UNITED STATES PATENT OFFICE.

JOHN F. MANN AND HENRY MANN, OF BROOKLYN, E. D., NEW YORK.

DESIGN FOR CLOCK-CASES.

Specification forming part of Design No. 6,800, dated August 12, 1873; application filed July 17, 1873.

To all whom it may concern:

Be it known that we, JOHN FERDINAND MANN and HENRY MANN, both of the city of Brooklyn, E. D., in the county of Kings and State of New York, have invented a new and original Design for Clock-Fronts; and we do hereby declare the following to be a full, clear, and exact description thereof, which will enable those skilled in the art to make and use the same, reference being had to the accompanying drawing forming part of this specification, in which drawing my design is fully represented.

The letter A in the drawing designates the front of a clock, on which is formed an ornamental head or cornice, B, and a base or pedestal, C. Said cornice B is shown as being supported on opposite sides by brackets a, and a crown or shield, b, is formed on the apex thereof. On the base C are represented a group of three persons, D E F, interspersed

with fowls, and a portion of a rustic fence is shown in the background of such group, while the whole is tastefully ornamented with leaves or foliage in such a manner that a rural and picturesque appearance is given to our clock-front, whereby the same can be readily distinguished.

What we claim as new, and desire to secure by Letters Patent, is—

1. The design of the cornice B, as shown and described.
2. The design of the base or pedestal C, as shown and described.

This specification signed by us this 8th day of July, 1873.

JOHN FERDINAND MANN.
HENRY MANN.
